DESIGN FOR A CANDELABRA

Mildred Bryant Brooks, South Pasadena, Calif.

Application December 17, 1941, Serial No. 104,681

Term of patent 7 years

To all whom it may concern:

Be it known that I, Mildred Bryant Brooks, a citizen of the United States, residing at South Pasadena, in the county of Los Angeles and State of California, have invented a new, original, and ornamental Design for a Candelabra, of which the following is a specification, reference being had to the accompanying drawing, forming part thereof.

Fig. 1 is a view in front elevation of the candelabra embodying my new design; and Fig. 2 is a top plan view of the same.

I claim:

The ornamental design for a candelabra, as shown.

MILDRED BRYANT BROOKS.
